UNITED STATES PATENT OFFICE.

MORRIS E. STANTON, OF RICHMOND, INDIANA, ASSIGNOR TO F. & N. LAWN MOWER COMPANY, OF RICHMOND, INDIANA, A CORPORATION.

DESIGN FOR A LAWN-MOWER CASING.

No. 38,341.

Specification for Design.

Patented Dec. 4, 1906.

Application filed August 29, 1906. Serial No. 332,543. Term of patent 14 years.

To all whom it may concern:

Be it known that I, MORRIS E. STANTON, a citizen of the United States, and a resident of the city of Richmond, in the county of Wayne and State of Indiana, have invented a new, ornamental, and original Design for Lawn-Mower Casings, of which the following is a complete and accurate specification.

In the accompanying drawings, forming a part of this specification, Figure 1 shows an outside elevation of one end of a lawn-mower casing having my invention, and Fig. 2 shows an inside elevation of the same.

Said views when taken collectively exhibit all of the essential features of my design, it of course being understood that the other side of the lawn-mower is a duplicate of the side shown and above referred to.

I claim—

The ornamental design for a lawn-mower casing, as shown.

MORRIS E. STANTON.
